Primary Examiner — Llorellys Martinez*(74) Attorney, Agent, or Firm* — Wood Herron & Evans LLP(57) **CLAIM**

The ornamental design for a lawn edging connector, as shown and described.

DESCRIPTION

FIG. 1 is a front perspective view of a lawn edging showing our new design;

FIG. 2 is a front view thereof;

FIG. 3 is a rear view thereof;

FIG. 4 a right side view thereof;

FIG. 5 is a left side view thereof;

FIG. 6 is a top view thereof; and,

FIG. 7 is a bottom view thereof.

The broken lines in the drawings illustrate portions of the lawn edging connector that form no part of the claimed design. The lawn edging connector is shown with a symbolic break in its length and height. The appearance of any portion of the lawn edging connector between the break lines forms no part of the claimed design.
